PAPER TOWELING

Karl J. Moe, Neenah, Wis., assignor to Fort
Howard Paper Company

Filed Jan. 26, 1972, Ser. No. 221,135

Term of patent 14 years

Int. Cl. D6—13

U.S. Cl. D59—2 B

FIG. 1.

FIG. 2.

FIG. 3.

FIG. 1 is a schematic plan view of paper toweling showing my new design, a full width of the design is shown with the design unit being repeated in regular succession to an indeterminate length, the dash lines representing the serrations between two paper towel sections;

FIG. 2 is an enlarged plan view of my new design showing the portion to the left of FIG. 1, the background configuration of the paper toweling being shown at the lower left corner, the remainder of the background having been omitted for convenience of illustration; and

FIG. 3 is an enlarged plan view, similar to FIG. 2, but showing the portion to the right of FIG. 1.

In the lower right-hand corner of FIGS. 2 and 3, the small squares have been lined for color, the remainder

of the shading for these squares having been omitted for convenience of illustration.

I claim:

The ornamental design for paper toweling, as shown and described.
